Primary Examiner — Mehri F Bajoul(74) *Attorney, Agent, or Firm* — Patterson + Sheridan, LLP(57) **CLAIM**

The ornamental design for a game, as shown and described.

DESCRIPTION

FIG. 1 is a top, front, right perspective view of a game showing our new design.

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a top plan view thereof.

The broken lines shown in the drawings depict portions of the game layout that form no part of the claimed design.

1 Claim, 6 Drawing Sheets(56)
